[57] CLAIM

The ornamental design for a control panel for a combined vehicular radio receiver, cassette player, compact disc player and digital clock, as shown and described.

DESCRIPTION

FIG. 1 is a top, front and left side perspective view of a control panel for a combined vehicular radio receiver, cassette player, compact disc and digital clock showing our new design;

FIG. 2 is a top plan view thereof;

FIG. 3 is a front elevational view thereof;

FIG. 4 is a bottom plan view thereof;

FIG. 5 is a left side elevational view thereof; and,

FIG. 6 is a right side elevational view thereof.

The broken line showing is for illustrative purposes only and forms no part of the claimed design.
